UNITED STATES PATENT OFFICE.

ALVEY J. RICE, OF LAWRENCEBURG, KENTUCKY, ASSIGNOR OF ONE-HALF TO THOMAS B. McGURK, OF McBRAYER, KENTUCKY.

ELECTRICAL ALARM DEVICE.

993,460.

Specification of Letters Patent. Patented May 30, 1911.

Application filed April 27, 1910. Serial No. 557,970.

To all whom it may concern:

Be it known that I, ALVEY J. RICE, a citizen of the United States, residing at Lawrenceburg, in the county of Anderson and 5 State of Kentucky, have invented certain new and useful Improvements in Electrical Alarm Devices, of which the following is a specification, reference being had to the accompanying drawings.

10 This invention relates to improvements in electrical alarm devices and has for its object to provide an extremely simple device of this character which is especially designed and adapted for use in flour mills and operates to cause an alarm when the delivery 15 chute becomes choked with flour.

A further object is to provide an extremely simple alarm device wherein an electric circuit is adapted to be automatically closed to 20 ring a bell or operate the desired signal so that the delivery spout may be immediately opened and the liability of waste thereby eliminated.

With these and other objects in view, the 25 invention consists of the novel features of construction and the combination and arrangement of parts hereinafter fully described and claimed, and illustrated in the accompanying drawings, in which—

30 Figure 1 is an elevation of the flour spout showing my improved signaling device arranged therein, the cover board being broken away; Fig. 2 is a section taken on the line 2—2 of Fig. 1; and Fig. 3 is a bottom plan 35 view of the spout section carrying the signaling device.

Referring more particularly to the drawings 5 indicates a rectangular spout or chute through which the flour descends. One of 40 the greatest difficulties in the milling of flour is to keep the chutes or spouts open. They are constantly becoming choked and often require the machinery to be stopped and also result in considerable waste of the 45 flour. In order to overcome these difficulties, I cut out a section of one side of the spout adjacent to its lower end and in such cut away portion a porcelain slab or base 6 is inserted. This base may also be formed of 50 hard rubber or other suitable insulating material and is securely held in such cut away portion by means of the turn buttons 7 which are arranged above and below the same upon the side of the spout 5.

55 Upon the outer face of the insulating slab

6, the binding posts 8 are arranged. To these binding posts the circuit wires of an electric battery 9 are connected, a bell 10 or other suitable signaling device being arranged in said circuit. Beneath one of the 60 binding posts 8 a contact plate 11 is secured, said plate being angularly bent and disposed in spaced relation to the insulating slab 6. Upon the inner face of said slab a flexible sheet metal plate 12 is secured at one 65 end by the screw 13 which fastens the other of the binding posts upon the outer face of said slab. This plate normally extends into the chute from the screw 13 at an angle to the slab 6 and has secured adjacent to its 70 free end a contact rod 14 which is movable through an opening 15 provided in the slab 6, said opening being disposed opposite to the contact plate 11. In order to protect the contact plate 11 and the binding post, a 75 cover board 16 is arranged thereover, the end of said board being secured to the spacing blocks 16' which are in turn secured to the sides of the discharge spout.

The plate 12 being connected to the primary of the electric circuit and the contact plate 11 to the secondary of said circuit, it will therefore be obvious that normally the circuit is broken when the movable plate 12 is disposed in the position illustrated in Fig. 80 2. If the chute or spout 5 begins to choke up at the bottom the accumulation of flour between the plate 12 and the opposite wall of the spout will gradually force said plate outwardly against the insulating slab 6. 90 When a sufficient quantity of flour has thus accumulated, its weight will move said plate to a sufficient extent to engage the end of the rod 14 carried thereby with the contact plate 11. The electrical circuit is thus connected and the bell or other signaling device operated so that the miller will know that the chute is becoming choked and can open the same without delay. This is usually 95 done by striking the sides of the spout with 100 a mallet or block of wood so as to dislodge the accumulated flour therein.

From the above it will be seen that I have provided a very simple and efficient device which is automatically actuated to 105 operate the alarm and relieves the miller of considerable extra work and anxiety. The waste of flour and loss of time which has heretofore been the result of the choking of the flour chutes in a milling establishment 110

is entirely eliminated and a device provided which is very positive in its operation, durable in use and may be manufactured at a very low cost.

5 While I have shown and described the preferred embodiment of my invention, it will be understood that the same is susceptible of many minor modifications without departing from the essential features or sacrificing any of the advantages thereof.

10 My improved signal device is also applicable to gravity conveyers which are utilized for conveying various other materials than flour, and it will be understood that I do 15 not wish to be restricted to the particular application of the invention as above set forth.

Having thus described the invention what is claimed is:

20 1. An alarm device of the character described comprising an insulating base, binding posts arranged upon said base, the wires of an electric circuit being secured to said binding posts, a resilient sheet metal plate 25 fixed at one end upon one side of the base and connected to one of said binding posts, a contact plate angularly bent intermediate of its ends and rigidly fixed at one of said ends to the other binding post, the free end 30 of said plate being disposed in parallel rela-

tion to the base and spaced therefrom, said base having an opening therein in line with the end portion of the contact plate, and a contact rod fixed at one end to said resilient plate and movable through the opening in 35 said base for engagement with said contact plate to connect the electric circuit.

2. An alarm device of the character described comprising an insulating base, binding posts arranged upon said base, the wires 40 of an electric circuit being secured to said binding posts, a resilient sheet metal plate fixed at one end upon one side of the base and connected to one of said binding posts, said plate extending from its fixed end at 45 an angle to the face of said base, a contact plate secured upon the other face of the base by the other binding post, the end of said plate being spaced from the base, said base having an orifice therein, and a contact rod 50 fixed upon the free end of the resilient plate for movement through said orifice into engagement with said contact plate to connect the electric circuit.

In testimony whereof I hereunto affix my 55 signature in the presence of two witnesses.

ALVEY J. RICE.
